KNITTED FABRIC

Filed May 21, 1930

UNITED STATES PATENT OFFICE

VINCENT LOMBARDI, OF BROOKLYN, NEW YORK

KNITTED FABRIC

Application filed May 21, 1930. Serial No. 454,293.

This invention relates to the manufacture of knitted fabrics with the object in view of providing an improved knitted fabric consisting of a plurality of independent yarns arranged in different manners in different parts of the fabric to produce a variety of pleasing pattern effects. In one embodiment of the invention the fabric may comprise at least three portions of different characteristics employing for example two independent yarns. In one portion one yarn may be looped with the second yarn unlooped and lying in the rear of the fabric but drawn taut to cause the looped yarn to form a ridge; in a second portion the second yarn may be looped with the first yarn unlooped and lying behind the rear of the fabric but drawn taut to cause the looped yarn to form a second ridge separated from the first ridge by the valley caused by changing the knitting from the first yarn to the second yarn; and in a third portion to have alternate rows of loops of the two yarns. This combination gives a very pleasing effect by means of which a variety of pattern effects may be made prominent in the resulting fabric.

The invention will be better understood by reference to the following detailed description taken in connection with the accompanying drawings in which

Fig. 1 illustrates one pattern effect which may be produced by this invention:

Fig. 2 illustrates a variation of the pattern effect of Fig. 1;

Fig. 3 illustrates still another possible variation of the fabric of Fig. 1;

Fig. 4 represents the details of the looped and unlooped portions of the yarns making up the fabrics of Figs. 1, 2, or 3;

Fig. 5 represents schematically the thickness of the fabric in the various wales of the upper portion of Fig. 4;

Fig. 6 represents schematically the thickness of the fabric in the various wales for the lower portion of Fig. 4; and

Fig. 7 shows the details of the knitting when a portion of the fabric is of the interlock type.

Referring first to the knitted fabric of Fig. 4, the fragment of the fabric shown is com-

posed of two independent yarns 11 and 12 and is divided into three portions, designated as A, B, and C. Each portion is three wales wide and in the A portion the yarn 12, for example is formed into loops in the three wales thereof while the yarn 11 lies entirely behind all three wales of yarn 12. In the top part of section B the situation is just the reverse in that yarn 11 is formed into loops in three wales while the yarn 12 is unlooped and lies entirely behind the three wales of the yarn 11. In section C both yarns 11 and 12 are knitted into loops in alternate rows. This means that the loops in section B are twice the size of the loops in section C. If we follow yarn 12a for example, we will see that it forms large loops in three wales in section A, lies behind the fabric in section B and forms small loops in three wales in section C. Yarn 11a lies behind the loops in section A, forms large loops in three wales in section B and forms small loops in three wales in section C. The next passage of yarn 12 is designated 12b in Fig. 4 and it will be noted that the path of yarn 12b is the same as for yarn 12. Similarly yarn 11b corresponds to yarn 11a. If we proceed farther down the fabric it may be noted that in one passage of yarn 11, called yarn 11c, the said yarn is behind the wales in section A but is formed in small loops in both sections B and C. Also one passage of yarn 12, called yarn 12c, the said yarn is formed in loops in section A and is formed in small loops in both sections B and C.

It may be assumed by way of example that yarn 11 is white and yarn 12 is black. In order to obtain the desired effect, yarn 11 must be pulled fairly taut in section A which will cause the three wales of yarn 12 to be bowed out to form a prominent ridge as shown in Fig. 5 where in section A yarn 11 is shown as a straight line sufficiently short that the three loops of yarn 12 are bowed out to give them prominence. That is if we assume that the three loops of yarn 12 would have a certain width lying flat then the amount of yarn 11 allotted to lie behind the said loops is considerably shorter than said width, so that the said loops are prevented from lying flat.

but of necessity must bulge out until their effective width equals the length of yarn 11 lying behind them. The manner in which yarn 11 is looped in adjacent sections prevents yarn 11 in section A from being increased in length to allow the said loops to lie flat. Similarly the amount of yarn 12 in the upper portion of section B, Fig. 4 is small enough to bow out the loops of yarn 11 there-
 5 in as shown in section B, Fig. 5. In section C however, where both yarns are formed into loops and the fabric is relatively flat as compared with sections A and B, see Fig. 5. The relative thicknesses of sections A, B and C for
 10 the lower portion of Fig. 4 which includes yarns 11c and 12c is shown in Fig. 6 where it will be noted that both sections B and C are flat, with a ridge in section A.

There is a marked valley or dividing line
 20 between sections A and B, between the last wale of section A and the first wale of section B, where one yarn after forming loops goes behind the fabric while the other yarn pursues the opposite path. Due to the special
 25 feature of the shortness of yarn 11 in section A and the shortness of yarn 12 in section B, section A will constitute a prominent ridge black in color, while section B will constitute a prominent ridge white in color, with section
 30 C constituting a relatively flat portion mixed in colors. This gives the fabric three different characteristics which may be used to vary the pattern design of the fabric in any way desired.

35 For example, ridges 8 of Fig. 1 may be of the white yarn 11, while ridges 9 may be of the black yarn 12 arranged in the manner shown in sections B and A of Fig. 4. Part 10 of Fig. 1 may correspond to the flat type of
 40 knitting shown in section C Fig. 4. A different arrangement of the ridges 8 and 9 and flat knitting 10 is shown in Fig. 2 wherein the ridges 8 and 9 and the flat knitting 10 alternate in blocks of equal size. In Fig. 3 the
 45 major portion of the fabric is of the flat or jersey type 10 while the white ridges 8 and black ridges 9 are only a few rows in length as compared to Figs. 1 and 2. Figs. 1, 2, and 3 are merely illustrative of a wide variety of
 50 pattern effects that may be secured by the present invention.

In order that the tight yarn 11 behind the loops in section A of Fig. 4 may produce the desired bulge in the loops, the number of
 55 wales in section A should not exceed five or seven and the best results are obtained with only three wales or less. Any large number of wales in section A will defeat the purpose, that is a pleasing bowed out effect of the
 60 loops will not result. A similar consideration applies to section B of Fig. 4.

Another form that this invention may possess is shown in Fig. 7 where the fabric is divided into three sections designated D, E and
 65 F. Section D corresponds to section A of

Fig. 4 and one yarn 21 is looped therein in three wales, while a second yarn 20 lies behind the said loops in such a manner as to cause the said loops to be bowed out. In section E the yarn 20 is looped in three wales while yarn 21 lies behind the wales, corresponding to section B of Fig. 4. In section F however, loops of yarn 21 are formed but the yarn 20 instead of lying entirely behind all the loops is interlocked between the loops in alternate wales as described in detail in my U. S. Patent, No. 1,426,576 issued Aug. 22, 1922. Section F is therefore of the interlock type but does not form a ridge as section E or D although it will have a somewhat thicker appearance than the jersey stitch of section C Fig. 4. In other words the difference between the appearance of sections E and F are so marked that they may be used to give any pattern effect desired. The preferred limitation of sections D and E to three wales or less does not of course apply to section F which may be of a large number of wales. Thus the main body of the fabric may be like section F while isolated portions may
 70 be like section D or E. It is of course to be understood that still another portion of the fabric of Fig. 7 may comprise a jersey stitch such as in section C of Fig. 4 wherein both
 75 yarns 20 and 21 form loops.

80 It will be noted that in the lower part of Fig. 7 yarn 21c is formed into loops in all three sections, while yarn 20c is entirely behind the loops in section D and is interlocked in alternate wales in both sections E and F.

85 The above described forms of the invention are given by way of examples only, and it is to be understood that the invention may possess still other embodiments as defined in the appended claims.

90 The invention claimed is:

1. A knitted fabric of a plurality of independent yarns, one portion of said fabric comprising one of said yarns looped in seven or less wales and in a plurality of rows, another of said yarns in an unlooped portion passing entirely behind said loops of one row and in a direction at right angles to one of said wales, said unlooped portion of yarn being of such a length that the loops of said
 95 one row are bowed out to a distance greater than the average thickness of the fabric to form a ridge parallel to said wales even when the fabric as a whole is under moderate tension.

100 2. A knitted fabric comprising a plurality of independent yarns, one of said yarns forming loops in a plurality of wales and a plurality of rows in a first portion and in a second portion of the fabric, said portions being separated by a third portion comprising a second
 105 yarn looped in seven or less wales and in a plurality of rows, said first yarn being unlooped in said third portion and being stretched entirely behind and across said

seven or less wales, the length of said one yarn
behind said wales being substantially less
than the total normal width of said wales to
cause said wales in said third portion to be
bowed out away from the stretched portion
of said first yarn a distance greater than the
average thickness of the fabric.

5 In witness whereof, I hereunto subscribe
my name this 14th day of May, 1930.

10 VINCENT LOMBARDI.
